FIG. 1.

FIG. 2.

FIG. 3.

FIG. 4.

FIG. 5.

INVENTOR.
John T. Rudzinski
BY *Robert H. Polansky*
ATTORNEY

UNITED STATES PATENT OFFICE

JOHN T. RUDZINSKI, OF NEW YORK, N. Y.

HIP-REDUCING GARMENT

Application filed September 19, 1928. Serial No. 306,818.

This invention relates generally to garments and has more particular reference to a hip reducing garment.

The invention has for an object the provision of a device of the class mentioned, which is of simple durable construction, desirable in use and efficient in action, and which can be manufactured and sold at a reasonable cost.

The invention proposes the use of a hip line reducing garment with usual features in the way of correcting the posture and supporting the figure combined with ability of reducing one's weight. Startling results in appearance are obtained on proper adjustment of the garment as directed by a navel engager member, and positive reducing is assured in a few weeks of wearing.

One object of my invention is to produce a new and improved one-piece garment without stays and harsh steels for molding the figure like a glove and made from ventilated porous fabric which washes like a handkerchief. It has thus, exclusive features that make it different and far better than any other garments.

In the accompanying drawing, forming a material part of this disclosure:—

Fig. 1 is a perspective view of the article applied upon a wearer.

Fig. 2 is a similar view showing the rear side thereof.

Fig. 3 is an enlarged fragmentary detail view of the front portion of the device.

Fig. 4 is a central vertical sectional view, taken on the line 4—4 of Fig. 3.

Fig. 5 is a view similar to Fig. 3, but disclosing a modification thereof.

The reference numeral 10 indicates generally the front portion of the garment arranged for covering one's hips and extending upwards to cover the breast. This front portion is provided with bust reinforcement straps 11 and a pair of front curved vertically arranged reinforcement straps 13. Side reinforcement straps 14 extend from the top to the bottom of the garment, and transverse reinforcement straps 15 on the hip line of the garment extend between the reinforcement straps 13 and 14.

The rear portion 16 of the garment is in-

tegral with the front portion and has a central vertical gusset 17 of elastic material extending from the top edge completely to the bottom edge. A pair of rear vertical reinforcement straps 18 also extend from the top to the bottom, and transverse reinforcement straps 19, substantially on the hip line extend between the straps 18 and the gusset 17.

On the inner side of the garment and on the front portion thereof between the front curved reinforcement straps 13, a navel engager member 20 of felt is secured by means of stitches 21. The garment is shaped to present graceful lines, and the navel engager member 20 should be aligned with the navel so as to insure the proper wearing of the garment, that is for wearing the garment at the proper height. Obviously no matter how skillful the lines of the garment are made, if not properly worn it will defeat its graceful appearance. The navel engager 20 indicates the proper wearing position of the garment. The garment is provided with shoulder straps 28.

In operation of the device it is engaged upon the wearer by stretching the gusset 17. Thus engaged a pressure exists which acts to produce a stress on the wearer's body, tightening the wearer's muscles using up excess fat, and thus serving as a reducing agent. The loss of weight is accomplished similar to massaging but of course, there is no moving massaging action, the pressure is depended upon to produce the same results.

In addition, the porous condition of material, preferably chiffon, acts to permit for the proper ventilation of the article. Usually, garments of this class are improperly worn and this renders them inefficient. In the instant case the garment may be properly worn as directed by the navel engager as before described.

In the modified form of the device illustrated in Fig. 5 a navel engager member is illustrated having a front headed end 22 passing through a vertical slot 23 formed in the material of the garment. The edges of the slot are reinforced by stiffening edges 24. A thin wire 25 passes through the head 22, and has hooks 26 at its ends engaging comple-

mentary fastening eyes 27 attached on the vertical reinforcement straps 13, and these fastening eyes 27 are arranged in vertical rows. It is readily seen that the position of the member 20 may be adjusted by engaging the hooks on different eye members for better adapting the garment to different individuals.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a garment of the class described, front material formed with a vertical slot, a navel engager having a headed end passing through the vertical slot, a thin wire passing through the headed end, a vertical row of eye fasteners attached on the material of the garment on each side of the vertical slot, hooks secured to the free ends of the thin wire engageable in the vertical rows of eye fasteners for holding the navel engager in adjusted positions.
2. In a garment of the class described, front material formed with a vertical slot, a navel engager having a headed end passing through the vertical slot, a thin wire passing through the headed end, a vertical row of eye fasteners attached on the material of the garment on each side of the vertical slot, means for engaging the thin wire in the vertical rows of eye fasteners for holding the navel engager in adjusted positions.

In testimony whereof I have affixed my signature.

JOHN T. RUDZINSKI.
